STROKE CONTROL MECHANISM FOR PUMPS

Peter Kristoffer Seter, Milwaukee, Wis.

Application August 26, 1953, Serial No. 376,564

1 Claim. (Cl. 103—38)

This invention relates to improvements in stroke control mechanism for chemical or hydraulic pumps of the general type shown and described in my prior Letters Patent No. 2,564,793, dated August 21, 1951.

One of the objects of the invention is to provide a micrometer adjusting means which is contained wholly within the pump gear case, and is completely immersed in oil at all times to insure proper lubrication of the working parts.

Another object of the invention is to provide a control mechanism for a pump stroke in which maximum and minimum adjustments are readily obtained and accurately determined through the operation of a single element, the single adjusting element being available for adjustment through a normally covered opening formed in the gear case of the assembly.

A further object of the invention is to provide a control mechanism in which the range of movement of the adjusting parts is constant throughout the limits of the adjustment and the parts of the adjusting mechanism are suspended in a position to maintain the adjusting element permanently available for manipulation regardless of the position of the pump mechanism.

Other objects of the invention reside in the novel construction and arrangement of parts, whereby critical adjustments are available at all times and the adjustments are permanent in character in that variation from a stipulated adjustment during normal operation of the pump is not possible.

Other objects of the invention will more clearly hereinafter appear by reference to the accompanying drawings forming a part of the instant specification, wherein like characters of reference designate corresponding parts throughout the several views, in which:

Fig. 1 is a top plan view of the assembly;

Fig. 2 is a vertical section on line 2—2 of Fig. 1;

Fig. 3 is a transverse section on line 3—3 of Fig. 2;

Fig. 4 is a sectional view on line 4—4 of Fig. 3;

Fig. 5 is a view of the control mechanism adjusted for minimum stroke;

Fig. 6 is a similar view showing the arrangement of the stroke mechanism for maximum adjustment of the stroke with the minimum adjustment illustrated in dotted lines; and

Fig. 7 is a perspective view of the adjusting mechanism.

In the disclosure of the instant invention the pump assembly includes a rectangular gear housing including base plate 1, side walls 2 and 3, end walls 4 and 5, and cover plate 6. The base plate 1 is shown as projecting beyond the side walls 2 and 3 of the gear housing to provide for the utilization of the securing means, illustrated as stud bolts 7. The front end wall 5 is formed with an opening 8 through which a portion of the pump cylinder structure extends, to be hereinafter described, while the rear end wall 4 is formed with an opening for the reception of the main drive shaft 9, as best shown in Figs. 1 and 2. The cover plate 6 is provided with an opening 10 positioned to provide access to the control mechanism,

2

the opening 10 normally being covered by a cap plate 11 pivotally mounted on the pivot pin 12.

The assembly will normally be driven from an electric motor, through a V-belt 14, which drives the shaft 9 through the pulleys 15 mounted thereon, the shaft 9 being mounted in bearings 16 and 17 supported on the inner faces of the end walls 4 and 5 of the housing. The drive shaft 9 is provided with a worm gear 18 which drives the gear 19 which is keyed to and drives at relatively low speed the transverse shaft 20 mounted in bearings 21 and 22 supported by the side walls 2 and 3, respectively. The bearing 22 is fixed to removable wall plate 23 secured to the side wall 3 by bolts 24 to permit removal of the bearing 22, and assembly and disassembly of the mechanism when necessary. Fixed by keying or otherwise, a cam 25 is secured to the shaft 20 driven by the gear 19 through the worm 18 from the source of power.

The pump assembly includes the pump cylinder 30 having inlet connection 31 and outlet connection 32, these inlet and outlet connections being provided with the dual check valves 33 and 34, respectively, to provide for the flow of material into and out of the pump cylinder. The pump cylinder 30 is supported by the pump casting 35, the latter having the reduced inner extremity 36 which projects through the opening 8 in the front wall 5 of the gear housing, the pump casting including a packing box in which the packing 37 is arranged and this packing 37 is adjustable by means of packing nut 38, as shown in Fig. 2. The pump piston is shown as sealed by packing 39, adjusted by means of packing nut 40 and lubricated through the lubricant passageway control mechanism as at 41 medially of the packing. The pump piston is shown at 42 and is pivotally connected by pivot pin 43 to the push rod 44. The push rod 44 operates through the packing 37 heretofore mentioned and the pivot pin 43 permits sufficient flexing of the piston drive mechanism to perform the required function. An indicator disc 45 is illustrated at the joint between the piston 42 and the push rod 44, this indicator disc being associated with a scale 46 on the pump casting for checking the pump stroke.

The drive transmission between the cam 25 mounted on the driven shaft 20 in the gear box and the push rod 44 includes the micrometer control by means of which the stroke of the pump may be regulated and predetermined in accordance with requirements. This control mechanism is mounted on a pivot pin 50 which is bolted to the vertical side wall 2 of the gear housing and includes a forked member having an upper bearing 51 mounted on the pivot pin 50, the outer arm of the forked member being indicated at 52 and projecting rearwardly and downwardly as at 53 to engage the back face of the cam 25. The front arm 54 of the forked member extends downwardly and embraces the front face of the cam 25, as shown in Fig. 2, these arms 52 and 54 being properly spaced to provide just sufficient clearance for the proper operation of the parts by the cam. The arm 52 is sufficiently resilient and reduced at its depending portion 53 in a manner to provide proper facilities for adjusting the spacing between the arms and simultaneously providing essential resiliency between the face surfaces abutting the cam 25.

The forked arm 54 is formed with a milled slot 55 which extends transversely through and from one end of the forked arm 54 to a point 56 adjacent the upper extremity of the arm. Formed medially of the longitudinally extending slot and longitudinally of the forked arm 54, is a bore 57, see Fig. 4, and in the annular bore 57 is positioned a slideable cylindrical block 58, see Fig. 3, this slideable block 58 being provided on opposite sides with projecting bearings 59 and 60, these bearings extending laterally through the milled side walls of the slot

55 and connecting with the extremities of a yoke member 61, as best shown in Fig. 7. The bearings 59 and 60 are clamped to the extremities of the yoke 61 by cap plates 62 secured in position by stud bolts 63, as shown in Fig. 4. The base 64 of the yoke member 61 terminates in a flat wall tongue element 65 which is secured by a pivot pin 66 to the bifurcated arms 67 of the push rod 44.

In the present development the screw 55 will be threaded to provide micrometer adjustments to permit regulation of the pump for minute variations in the discharge. The adjustment is made by swinging the cap plate 11 covering the opening in the cover plate 6 on its pivot, which will expose the upper extremity 68 of the screw 55, this upper extremity 68 being transversely slotted for the reception of a screwdriver or analogous implement. The rotation of the screw 55 will move the block 58 which is connected through the lateral projections 59 and 60 to the yoke member 61 to modify the stroke of the piston 42 in the pump cylinder 30. Figs. 5 and 6 show the approximate limitations of movement of the adjusted yoke.

It will be noted that the parts of the assembly are built to permit replacement and adjustment, the main bearing 22 being carried by the removable plate 23 in the side wall 3 of the gear housing. The removal of this bearing 22 obviously permits the disassembly or replacement of the drive mechanism and makes available the micrometer screw 55 and the related parts.

What I claim is:

In a pump assembly having a pump chamber and a piston reciprocable in the chamber, means for reciprocating the piston and varying the length of the stroke thereof, comprising a shaft including a cam on the shaft, means for rotating the shaft, a U-shaped member, a fixed pivot pin positioned adjacent the shaft, the U-shaped

member being pivotally mounted on the pin and having its arms straddling the said cam, an arm of said U-shaped member having a longitudinal bore therein, a block slideable in said bore, a screw threaded through said block and secured against longitudinal movement in the bore so that rotation of the screw will move the block axially in the longitudinal bore, the arm having oppositely positioned vertically extending slots therein, said block having bearing pins extending through said slots, a connecting rod having a forked end straddling the block and having its forks pivotally connected, one to each of the said bearing pins, and a piston pivotally connected to the connecting rod, rotation of the said screw moving the block toward or from the pivotal point of the U-shaped member and thereby varying the stroke of the piston.
